Primary Examiner — George A Bugg*Assistant Examiner* — Tamara L Hahn(74) *Attorney, Agent, or Firm* — Raymond Y. Chan; David and Raymond Patent Firm(57) **CLAIM**

The ornamental design for a snow brush, as shown and described.

DESCRIPTION

FIG. 1 is a perspective view of the snow brush showing my new design;

FIG. 2 is another perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is an exploded perspective view of FIG. 1, illustrating the snow brush being detached;

FIG. 10 is an exploded perspective view of FIG. 2, illustrating the snow brush being detached; and,

FIG. 11 is an enlarged perspective view of FIG. 9, illustrating a detachable joint of the snow brush.

The dot-dash-dot lines shown in the FIGS. 9 and 11 are to show enlarged portions of the snow brush and form no part of the claimed design.

1 Claim, 11 Drawing Sheets(56)
